UNITED STATES PATENT OFFICE.

JOHN McMILLEN, OF EAST BRANTFORD, COUNTY OF BRANT, ONTARIO,
CANADA.

HAY-KNIFE.

SPECIFICATION forming part of Letters Patent No. 351,196, dated October 19, 1886.

Application filed March 31, 1886. Serial No. 197,247. (No model.) Patented in Canada April 1, 1884, No. 19,002.

To all whom it may concern:

Be it known that I, JOHN McMILLEN, of East Brantford, in the county of Brant, in the Province of Ontario, Dominion of Canada, have 5 invented a certain new and useful Improvement in Hay-Knives; and I do hereby declare that the following is a full, clear, and exact description of the construction and operation of the same.

10 The invention relates to a very handy and convenient device for cutting hay, straw, or manure.

The device consists in a metal blade about from sixteen to eighteen inches in length and 15 three and a quarter inches broad, having an upward shank welded to it on the top side, so that when it is vertical the cutting-edge of the blade stands about at an angle of thirty degrees. To the upper part of said shank is attached a 20 horizontal foot-bar to receive the pressure of the foot in operating the device. The outer end of the said foot-bar is bent upward and made to enter the end of a wooden handle. At the junction of the foot-bar and shank there 25 is a small upward projection to prevent the operator's foot from slipping off when pressing on the foot-bar.

By reference to the drawing, forming part of this specification, it will be seen that in the 30 figure, A represents the steel blade set at the best cutting angle, as shown; C, the shank welded to the blade; C', the foot-rest upon which to press the foot to cause the knife to cut; a, the projection to prevent the foot from slipping off; B, the wooden handle for controlling the knife.

It will be observed that the upper part of

the shank C can be bent at right angles to the lower part to form the foot-rest C', or the latter welded to the shank in the same position. 40

The whole length of the instrument will be about from three and a half to four feet, and will perform the operation of cutting about one-half easier than by hand and twice as quick. 45

In operating the device the handle B is simply held in the hands and the operator places his foot on the foot bar C' and presses the weight of his body on it to make each cut into whatever substance he wishes to cut, the angle 50 of the knife being so set as to cause the least resistance and perform the work easily.

Having thus described my device and its advantages, what I claim as my invention, and desire to secure by Letters Patent, is— 55

1. In a hay, straw, or manure knife, the blade A, constructed in the form and angle as shown, and having the shank C attached about the center of it, and bent at right angles, as at x a, to form the foot-rest C' and stop a, and 60 terminating in a handle, B, affixed to the same, substantially as and for the purpose specified.

2. In a hay, straw, or manure knife, the combination of the blade A, the shank C, foot-rest 65 C', and handle B, substantially as and for the purpose specified.

Dated at Hamilton, Ontario, this 27th day of March, 1886.

JOHN McMILLEN.

In presence of—

CHAS. G. McMILLEN,
W. BRUCE.
